UNITED STATES PATENT OFFICE.

JOHN HEATH AND WILLIAM FROST, OF BURSLEM, COUNTY OF STAFFORD,
ENGLAND.

BLASTING-CARTRIDGE.

SPECIFICATION forming part of Letters Patent No. 358,611, dated March 1, 1887.

Application filed May 14, 1886. Serial No. 202,158. (No model.) Patented in England April 14, 1886, No. 5,222, in France June 12, 1886, No. 176,729, and in Belgium June 15, 1886, No. 73,490.

To all whom it may concern:

Be it known that we, JOHN HEATH and WILLIAM FROST, both of Burslem, in the county of Stafford, England, have invented 5 certain new and useful Improvements in Blasting and Shot-Firing in Mines, and in appliances relating thereto, (for which we have obtained patents in Great Britain, No. 5,222, dated April 14, 1886; in France, No. 176,729, 10 dated June 12, 1886, and in Belgium, No. 73,490, dated June 15, 1886;) and we do hereby declare that the following is a full, clear, and exact description of the invention, which will enable others skilled in the art to which it applies, 15 to make and use the same.

The present invention relates to that class of cartridges for blasting or mining purposes in which the explosive charge is surrounded by a flame-extinguishing medium, so as to 20 avoid igniting gases or fire-damp. It has been proposed to construct a blasting-cartridge of an outer shell or casing which contains the explosive charge completely surrounded by water.

25 My invention is designed to obviate certain objections possessed by such water-packed cartridges; and it consists in making the outer shell of the cartridge of some pliable or flexible material, and placing therein a filling of 30 a jelly-like consistency, in which the explosive charge is embedded. The jelly-like filling contains a sufficient amount of water in a state of absorption, so that it will serve the purpose of a flame-extinguishing medium 35 when the explosive charge is fired. The object of using a jelly-like packing or filling is to guard against the liability of the water leaking out, and to give such a consistency to the flame-extinguishing medium that it can 40 be more easily handled. Furthermore, such jelly-like filling serves to hold the explosive charge properly centered or in such position within the outer shell or envelope that it will always be surrounded on all sides by the flame-extinguishing medium.

The accompanying drawing shows in longitudinal section a blasting-cartridge constructed according to our invention.

The reference-numeral 1 designates an outer envelope or shell, which is made of strong 5 paper, cloth, or a combination of both, mackintosh, oiled paper, or any suitable water-proof, pliable, or flexible material. The object of making the envelope of some flexible material is to allow it to adapt itself to the 10 irregularities of the blast-hole. The said envelope or shell contains an explosive charge, 2, of gelatine, dynamite, cotton-powder, or any other strong explosive. With explosives that can be placed in water without impairing 15 their efficiency no covering is required; but other charges affected by water or moisture are surrounded by a wrapping or covering, 3, of some water-proof material. A detonating or fulminating cap, 4, is inserted into 20 the end of the explosive charge, and a safety-fuse, 5, extends from said detonator and goes through the contracted or gathered mouth of the envelope 1.

25 It will be understood that the material of the envelope or shell 1 is gathered around the fuse, and is tied by means of a string, 6, so as to close the mouth of the envelope and hold the fuse in place.

The envelope or shell 1 is filled with a 30 flame-extinguishing medium, 7, which consists of soap, starch, glue, and water. These ingredients are admixed in such proportions as to form a jelly-like mass, in which the water is held in a state of absorption. The 35 mass is of such consistency or stiffness that the explosive charge will be held therein in a properly-centered position, so as to be surrounded on all sides by the gelatinous or jelly-like mass. It will be understood that the latter is not liable to spill or leak out, and that it is less liable to percolate through the pores of the outer shell or envelope than water. Furthermore, a filling of a gelatinous material charged with water can be handled more con- 40 45 50 55 60 65 70 75 80 85 90

veniently than water, and in transportation there is no swash or displacement, as is the case with water.

What we claim is—

- 5 A blasting-cartridge consisting of an outer flexible envelope or shell, an explosive charge, means for firing the same, and a jelly-like flame-extinguishing medium containing water and completely surrounding the explosive charge, substantially as herein set forth.

In witness whereof we have hereunto signed our names in the presence of two subscribing witnesses.

JOHN HEATH.
WILLIAM FROST.
